UNITED STATES PATENT OFFICE.

BOZIL S. ROY, OF WORCESTER, MASSACHUSETTS.

CARD-GRINDING MACHINE.

SPECIFICATION forming part of Letters Patent No. 276,884, dated May 1, 1883.

Application filed November 27, 1882. (No model.)

To all whom it may concern:

Be it known that I, BOZIL S. ROY, of Worcester, in the county of Worcester and State of Massachusetts, have invented certain new

and useful Improvements in Card-Grinding Machines; and I declare the following to be a description of my said invention, sufficiently full, clear, and exact to enable others skilled in the art to which it appertains to make and use the same, reference being had to the accompanying drawings, which form a part of this specification.

This present invention relates to grinders for cotton-cards, the principal objects of my improvements being to provide an apparatus whereby self-stripper flats or the bars of automatic card - strippers can be conveniently ground and a convex curvature imparted to the faces thereof, so that the form of their working-sfaces will correspond to their curve of motion when the self-stripper is in operation on the carding-machine, thus enabling the entire face of the stripper-slat to be brought into proper working relation with the surface of the card-flats whereon it is operating, and the stripping operation thereby performed in a more thorough, economic, and satisfactory manner; to afford means for operating the card-flat supporters in a circular arc in opposite relation to the grinding-wheel, as hereinafter explained; to provide means for retaining and adjusting the card-flat supporters in relation to their carrying devices, and for setting them to proper position and preventing looseness in the guides; also, to afford means for the longitudinal vibration of the grinder-shaft by a worm, worm-wheel, and a cam, as hereinafter explained. These objects I attain by mechanism substantially such as shown in the accompanying drawings, and hereinafter described, the particular subject-matter claimed being definitely specified.

In the drawings, Figure 1 is a part front, part sectional, view of a card-grinding machine illustrating the nature of my invention. Fig. 2 is a plan view of the same, showing a top-flat and a self-stripper slat in position for grinding. Fig. 3 is an end view of the same, some of the upper portions being shown in section. Fig. 4 is a transverse section of a self-stripper slat, showing the convex curve of its face. Fig. 5 is a side view of mechanism for

vibrating the grinder-shaft longitudinally. Figs. 6, 7, and 8 show details of construction of the supporters or heads for sustaining the 55 stripper-slats while being ground.

In the drawings, A indicates the main frame, composed of end castings and horizontal girts, formed and arranged as shown, or in a suitable manner, for supporting the operating 6c mechanism.

B indicates a traversing grinding-wheel, (or, if preferred, a long grinding-cylinder,) mounted on the shaft B', which turns in bearings b on the top of the frame. The mechanism for 65 traversing the wheel B on its shaft or cylinder, having been heretofore patented, need not be herein described. Shaft B' is operated by belt from the lower or driving shaft. P.

C C indicate the heads or pocket-boxes for 70 supporting the top-flats T of carding-machines while grinding the card-teeth. Said heads are mounted on reciprocating standards C', working in guides C², and the pockets are adapted for regulation and adjustment by means of 75 screws or devices organized substantially as shown and described in my Letters Patent No. 230,065.

D D indicate heads or holding devices adapted for supporting a self-stripper bar or slat, s, 80 and for moving or vibrating it, in connection with the grinding-wheel, in such manner that the face of the slat-clothing will be ground to a convex cylindrical curve—as, for example, x v, Figs. 3 and 4, said curve being designed 85 to correspond with the concavity of the top slats of the cards, or with the curve of movement of the self-stripper bar itself when in operation upon the carding-machine, so that the entire surface of the clothing on the self-stripper will act in stripping the cards. By grinding the face of the self-strippers convex a much wider stripper-slat can be used, if desired, than would be practical if the face were straight. The heads or holders D are arranged 90 to move or vibrate in a circular arc of motion, or to so rock the self-stripper slat or bar, in connection with the grinding-wheel, that the grinding is performed on the proper and desired curvature. The holders D are mounted 100 on the inner ends of swinging arms E, the opposite ends of which are pivoted on projecting parts A² of the frame A, in such relation to the wheel that the vibration or swing of the

5c 45 50 55 60 65 70 75 80 85 90 95 100

arms will indicate the curvature of the face of the slat s , as desired. This curve should properly correspond with the curve on which the self-stripper works when on the carding-machine. The pivots e may be made adjustable toward or from the axis of the wheel to vary the degree of curvature when it is desired to grind self-stripper slats having differently-curved faces. The holders are made as shown in detail in Figs. 6, 7, and 8, the part D' being adjustable on its support laterally of the machine, and the pocket D^2 being adjustable, by means of screws d , to carry the stripper-slat to or from the wheel B . Said pocket D^2 is provided with a seat for the end of the slat s , and with a set-screw, d' , or equivalent means, for clamping the slat in position. E' indicates a rod or brace connecting the two arms E across the machine.

20 The arms E and holders D are vibrated from eccentrics F on the shaft F' by means of the lever G and connecting-links H and I , said lever being fulcrumed on the frame A , with the respective links joining its ends to the operating and operated parts, substantially as illustrated in Fig. 3.

25 The pocket-boxes C are operated from eccentrics F by means of the connecting-bars K , which are pivoted to the ends of the sliding standards C' , on which said holders are carried. The guides through which the sliding standards C' work are fitted with gibs c and screws c' , whereby the standards can be set up to a firm bearing for rigidly sustaining the holders and slat to the face of the grinding-wheel.

30 In some cases it is preferred to use a grinding-cylinder the full width of the card in place of the traversing grinder-wheel B . In such cases it is essential that said grinding-cylinder should have a short longitudinal vibratory action; and to effect this movement I employ the device illustrated in Fig. 5, which consists of a worm or screw, B^2 , fixed on the grinder-shaft B' , and a worm-gear, N , meshing therewith and supported by a suitable hanger, N' , mounted on the shaft B' and moving laterally therewith. To the side of said gear N is fixed an eccentric or cam, N^2 , that works between parallel guideways $o\ o$, fixed 35 on a projection or bracket, A^2 , on the main frame A , said guideways being located perpendicular, or nearly so, to the axis of the shaft B' . The shaft B' is allowed lateral play in its supporting-bearings b to a distance equal to the throw of the cam N^2 . Revolution of the shaft B' and worm B^2 causes the revolution of the gear N and cam N^2 , and the action of the cam between the stationary guides o moves the hanger N' , which, being confined by its bearings $w\ w$, embracing the worm-heads or collar, effects the movement of the shaft B' longitudinally in a very simple, easy, and efficient manner. The cylinder-grinder and the traversing

40 grinding-wheel may be made to be interchangeably placed in the bearings h , so that either 65 can be used, as required.

45 At the front of the machine, and supported in suitable bearings projecting inward from the forward girt, is a short revoluble grinding-cylinder, R , for the purpose of grinding hand-cards, and for similar work. Said cylinder R is operated by a belt, S , from the pulley R' on the main shaft P , as indicated.

50 What I claim as my invention, and desire to secure by Letters Patent, is—

55 1. The combination, with the traversing grinding-wheel B , of the supporting-arms E , having pocket mechanism D for holding a self-stripper-slat, swinging, for regulating the grinding of the surface, from a pivot or center located at the position that will give a radius of action corresponding to the radius of action of the self-stripper mechanism whereon the slat or bar is to be used, substantially as and for the purpose set forth. 85

60 2. The combination of the grinding wheel or cylinder B , the swinging arms E , pivoted at e , the holders or pockets D , adjustably mounted on said arms and adapted for retaining a self-stripper-slat, the operating-shaft F' , having eccentrics F , and the connections $H\ I$ and lever G for imparting vibratory movement to said arms, as shown and described. 90

65 3. The combination of the worm-screw B^2 , rigidly fixed on the grinder-shaft B' , the hanger N' , dependent from said shaft, with its boxes $w\ w$ embracing the ends of the screw-hub, the worm-gear N , journaled on said hanger and meshing with said worm-screw, the eccentric cam N^2 , fixed to and revolving with said gear, and the stationary parallel guides $o\ o$, embracing said cam and rigidly attached to the frame A or a projection thereon, said parts being constructed and organized for operation as hereinbefore set forth. 100

70 4. In a card-grinding machine, the combination of the grinding-wheel B , the adjustable card-flat supporters C , the reciprocating slides C' , the operating-pitmen K , and the guiding-brackets C^2 , provided with gibs c and pressure-screws c' , said parts being constructed and arranged as herein shown, for the purposes set forth. 105

75 5. The combination of the traversing grinding-wheel and shaft $B\ B'$, the adjustable supporters C , operating on slides C' , the adjustable supporters D , operating on swinging arms E , the eccentrics F , shafts F' and P , and operating-connections $H\ G\ I$ and K , substantially as shown and described. 115

80 Witness my hand this 16th day of November, A. D. 1882.
